UNITED STATES PATENT OFFICE.

SAMUEL J. BROWN, OF MAPLEWOOD, MISSOURI.

TOY.

Application filed January 2, 1928. Serial No. 78,865.

This invention relates generally to toys and more particularly to means for propelling the same.

The objects of the invention are to provide simple and inexpensive means for propelling various toys, such as boats, hydroplanes, and other objects floatable in water and to provide propelling means which do not necessitate expert adjustment and attention and which is inexpensive and safe to operate.

Further objects of the invention are to provide a power generating unit for propelling various structures in or above water, said unit having no movable parts or valves, thereby reducing to a minimum the danger of said engine or prime mover getting out of order.

Still further objects of the invention are to provide a boiler having pipe connections leading therefrom into the water, said boiler being so constructed that when heat is applied thereto the water is first drawn into said boiler and then forcibly discharged therefrom through said pipe connections, there being no valves or movable parts utilized in the operation of said boiler, the circulation of water through the boiler being accomplished through the particular arrangement of the boiler and the pipe connections.

Additional objects of my invention are to provide an improved burner employing a suitable screen for preventing the spreading of the flame and centralizing the latter under the boiler.

With these and other objects in view my invention consists in certain novel features of construction and arrangement of parts, hereinafter more fully described and claimed, and illustrated in the accompanying drawings, in which—

Figure 1 is a side elevational view of a toy boat equipped with my improved propelling means and burner therefor.

Figure 2 is a top plan view of the same.

Figure 3 is a vertical transverse cross section taken on line 3—3 of Figure 1.

Figure 4 is a vertical transverse cross section taken on line 4—4 of Figure 1.

Figure 5 is a vertical cross section through the burner end of the boat and showing the boiler and the burner in side elevation.

Figure 6 is a top plan view of the boiler partly shown in cross section.

Figure 7 is a vertical cross section taken on line 7—7 of Figure 5.

Figure 8 is a top plan view of the burner.

Figure 9 is a detail construction of the boat balancing means.

Referring by numerals to the accompanying drawings 10 indicates an object which it is desired to propel, in the present instance, a toy boat having a hull 11, a keel 12, and a removable top or deck 13, the front end 14 of which is hinged at 15 to provide access to the interior of the boat. A rudder 16 is used to steer the boat and is formed of pliable material so that it may be bent to either side to steer the boat as desired. 70 Hinged cover 14 is provided with a socket 17 for receiving a flag or other suitable banner 18, while the rear end of cover 13 carries an imitation gun 19 which is swiveled thereon so that it may be swung about its axis thereby helping to balance the boat. The barrel of this gun is preferably filled with lead as indicated at 20 in order to provide suitable balancing means.

A boiler 21 preferably of circular shape 80 is arranged within the hull 11 and is supported therein by pipe connections 22 which are connected to said boiler and extend a suitable distance rearwardly therefrom and are then bent downwardly and extend outwardly through the bottom wall of the boat as indicated at 23 and terminate in horizontally disposed portions 24 arranged at each side of rudder 16, as shown in Figures 1 and 2. Boiler 20 preferably comprises a 90 bottom wall 25, annular wall 26, and top wall 27, the latter being curved inwardly so that the central portion of said top wall is spaced only a short distance from the bottom wall as shown in Figure 7, thereby providing an annular space 28.

Pipes 22 are connected to the annular wall 26 of boiler 21 at points spaced equidistant from the longitudinal center line of the boat as shown in Figure 6 and the points of communication between the space 28 and pipes 22 are substantially tangentially disposed relative to the boiler. The heat is applied to the boiler by means of a burner 29 which is located in the hull 11 below boiler 21 and preferably consists of a can 30 of suitable size and filled with suitable heating medium, such as canned heat, which can be ignited through aperture 31 formed in the top wall of said can. In order to prevent 110

spreading of the flames and localize the latter directly under the boiler, a screen 32 is fitted over the burner 30 and curves upwardly a suitable distance above aperture 31 so as to bring the heated portion of the screen the desired distance below the boiler. Burner 29 is provided with a handle 34 which extends longitudinally from said burner and terminates in an upwardly presented loop portion 35 by means of which burner 29 may be removed from the boat when cover 14 is moved upwardly as shown in dotted lines in Figure 5. Cover 14 and the rear portion of deck 13 are provided with suitable 10 ventilator openings 36 by means of which the circulation of air around burner 29 is assured. If desired, apertures 37 may be formed in the raised portion of deck 13 at points located within the lower ends of funnels 38, thereby providing additional ventilation for the burner.

In the operation of my device, assuming that the boat is placed in the water, when heat is applied to boiler 21, the air contained 25 therein is expanded and is expelled through one or both of pipes 22. The reaction produced by the expulsion of air from the boiler draws water into the boiler, which water upon being heated is discharged 30 through one or both of the pipes 22 in a similar manner and a new charge of water is sucked into the boiler. The discharge of water from the boiler through the pipes 22 propels the boat carrying the boiler forwardly. The forcible expulsion of water from the boiler through pipes 22 will continue as long as heat is applied to boiler 21 and the exposed ends 24 of pipes 22 are located within a body of water. The heated 40 water or steam may be discharged either through both of pipes 22 or through one of the pipes while the other pipe takes in a fresh charge of water.

The particular construction of the boiler 45 assists in quickly heating the water contained therein and facilitates the circulation of water through said boiler. Burner 29 is removable by means of handle 35 so that it can be refilled with the heating medium.

50 While I have shown and described my invention as applied to a movable object, it also can be used with stationary objects and in various modifications without departing from the spirit of my invention.

55 I claim:

1. A propelling device for floatable toys comprising a discoid boiler having rigid walls and having one of the horizontally disposed walls being so inwardly formed as 60 to almost touch the opposite wall, thereby forming an annular steam and water space tapering toward the center, and a pair of pipes communicating tangentially with said space and extending rearwardly from said 65 boiler.

2. A propelling device comprising a discoid boiler having a flat rigid bottom wall, a rigid top wall so inwardly curved as to almost touch said bottom wall, and an annular side wall thereby forming a horizontally 70 disposed circular boiler chamber tapering toward the center, and a pair of pipes connected at spaced points to said annular wall and tangentially communicating with the interior of said boiler. 75

3. A toy propelling device comprising in combination with a toy adapted to be disposed in a body of water, of a discoid boiler arranged within said toy, said boiler having a rigid top wall so inwardly curved as to 80 almost touch the bottom, thereby forming an annular steam and water space, a pair of pipes connected to the annular wall of said boiler, and extending rearwardly therefrom and terminating exteriorly of said toy with 85 in said body of water, and means for heating said boiler for inducing circulation of water through said pipes and said boiler.

4. A toy comprising a structure adapted to be arranged in a body of water, a discoid boiler disposed within said structure, said boiler having a rigid top wall so inwardly curved as to almost touch the bottom, thereby forming an annular steam and water space, a pair of pipes extending rearwardly 90 from said boiler and terminating exteriorly of said structure, and a burner removably arranged within said structure below said boiler for heating the latter and inducing circulation of water through said boiler and 95 said pipes. 100

5. A toy comprising a structure floatable in a body of water, a circular boiler arranged within said structure, said boiler having a rigid flat bottom wall, a rigid top wall so 105 inwardly curved as to almost touch said bottom wall and a rigid annular side wall, thereby forming an annular steam and water space tapering toward the center, a pair of pipes connected tangentially to the annular wall of said boiler and extending exteriorly 110 through the wall of said structure, the ends of said pipes terminating in said body of water below the plane of said boiler, a burner removably disposed within said structure below 115 said boiler, and a screen interposed between said boiler and said burner.

6. A toy comprising a structure floatable in a body of water, a circular boiler arranged within said structure, said boiler having a rigid flat bottom wall, a rigid top wall so inwardly curved as to almost touch said bottom wall and a rigid annular side wall, thereby forming an annular steam and water space tapering toward the center, a pair of pipes connected tangentially to the annular wall of said boiler and extending exteriorly through the wall of said structure, the ends of said pipes terminating in said 120 body of water below the plane of said boiler, 125

a burner removably disposed within said structure below said boiler, and a screen cap fitting over said burner and arranged therebetween and said boiler for preventing spreading of the flame of said burner.

5 7. A toy boat comprising a hull, propelling means for said boat comprising a discoid boiler having a flat bottom and an inwardly convexed top so disposed as to almost

10 touch said bottom, thereby forming an annular steam and water chamber, a pair of spaced pipes opening tangentially into said boiler chamber and extending rearwardly therefrom and terminating exteriorly of said

15 boat, said pipes being connected to said boiler at points tangentially arranged on the annular wall of said boiler, and a burner removably arranged in said hull below said boiler.

20 8. A toy boat comprising a hull, propelling means for said boat including a rigid discoid boiler having one of its walls so inwardly curved as to almost touch the opposite wall, thereby forming an annular steam

25 and water space, there being two passageways extending rearwardly therefrom and

terminating exteriorly of said boat, said pipes being connected to said boiler at points tangentially arranged on the annular wall of said boiler, a burner removably arranged in said hull below said boiler, and a weighted lateral extension pivotally secured to the deck of said boat and movable relative to the longitudinal axis thereof for balancing said boat.

30 9. A power generating unit comprising a discoid boiler having a flat bottom provided with an upwardly presented annular flange and an inwardly convexed top wall, said top wall being so curved as to almost touch the bottom, thereby forming an annular steam and water chamber tapering toward the center, all of the walls of said boiler being formed rigid, and a pair of pipes connected at spaced points tangentially to the annular wall of said boiler and having their ends terminating in a body of water below the horizontal plane of said boiler.

35 40 45 In testimony whereof I hereunto affix my signature this 29 day of December, 1925.

SAMUEL J. BROWN.
